LAWN SPRINKLER

Melvin G. Miller and Finis G. Yates, Houston,
Tex.; said Yates assignor to said Miller

Application April 9, 1952, Serial No. 19,266

Term of patent 14 years

(Cl. D91—1)

To all whom it may concern:

Be it known that we, Melvin G. Miller and Finis G. Yates, citizens of the United States, residing at Houston, in the county of Harris in the State of Texas, have invented a new, original, and ornamental Design for a Lawn Sprinkler, of which the following is a specification, reference being had to the accompanying drawings, forming a part thereof.

Figure 1 is a perspective view of a lawn sprinkler showing my new design;

Figure 2 is a rear elevational view thereof;

Figure 3 is a side elevational view thereof;

Figure 4 is a fragmentary front elevational view thereof; and

Figure 5 is a top plan view thereof.

We claim:

The ornamental design for a lawn sprinkler, as shown.

MELVIN G. MILLER.
FINIS G. YATES.
